UNITED STATES PATENT OFFICE.

ADOLPH M. HOLSTEIN, OF SYRACUSE, NEW YORK.

DESIGN FOR FURNITURE, CASKET, INTERIOR, OR EXTERIOR DECORATION.

52,096.

Specification for Design.

Patented June 11, 1918.

Application filed August 22, 1917. Serial No. 187,544. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Furniture, Casket, Interior, or Exterior Decoration, of which the following is a specification, reference being had to the accompanying drawing, forming a part hereof.

The drawing is a face view or front elevation illustrating my design.

This design consists of the representation of an oblique arrangement of bamboo rods in the general form of a quadrangle, the lowermost rodslapping each other at their contiguous ends and the two upper rods,

forming the sides of the quadrangle,lapping the lower rods and terminating short of each other and being crossed by obliquely arranged bamboo rods which cross each other within the quadrangle, the rods being entwined or interwoven in serpentine fashion with leaves and flowers in Oriental fashion.

I claim:

The ornamental design for furniture, casket, interior, or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
